UNITED STATES PATENT OFFICE

MICHAEL J. MCGUIRE, OF CHICAGO, ILLINOIS

TOBACCO POUCH

Application filed February 6, 1930. Serial No. 426,223.

This invention relates to tobacco pouches, and it has more particularly to do with a combined container for smoking tobacco and holder for a pipe, which may be conveniently carried in the pocket and handled with the same facility as an ordinary pouch in loading the pipe for use, and possessing the further advantage of a protective case for the pipe when not in use. The present invention is a direct improvement upon that set forth in my pending application filed June 8, 1929, and bearing Serial Number 369,329, and having for its principal object to make more practical the utility of the device, and to facilitate its manufacture. To this end the invention consists more particularly in the peculiar method of construction, and in the details of certain parts and combinations and arrangements thereof as hereinafter described and set forth in the appended claims.

In the accompanying drawings, illustrating a practical adaptation of the invention,—

Fig. 1 is a view with the outer casing shown in longitudinal section, and the interior lining and other structural features being shown partly in side elevation and partly in longitudinal section;

Fig. 2 is a section on the line 2—2 of Fig. 1;

Fig. 3 is a section on the line 3—3 of Fig. 1;

Fig. 4 is a view, partly in side elevation and partly in section, of the outer casing, with the interior parts removed therefrom; and

Fig. 5 is a section on the line 5—5 of Fig. 4.

Generally stated, the device comprises an outer casing 10, within which is provided a receptacle or pouch 11 for the tobacco and a separate receptacle for the pipe, comprising a portion 12 for the reception of the bowl and an angular extension 13 for the stem of the pipe. In this structure the opening of the casing preferably extends continuously along one side and one end thereof, and it is provided with a closure of the type known as the hookless fastener, in which there are a series of interengaging members on opposite sides of the opening which are brought into lock-

ing engagement with each other and also released by a sliding element. Preferably, as shown, the interengaging locking members, designated by the numeral 14, are attached to the marginal portions of a pair of fabric strips or tapes 15, which latter are inserted between the outer casing material 10 and a lining, to be now described.

The lining, which is preferably composed of a rubberized or other suitable airtight and moisture-proof fabric, comprises two side sheets 16 which are of the general marginal contour of the walls of the outer casing 10. At one end these sheets 16 are stitched, as at 17, or otherwise suitably secured to an interposed strip or gusset 18. The portion 19 of the gusset thus secured to the side sheets 16 of the lining, constitutes the end wall of the pouch or tobacco container of the device, and said gusset is carried forwardly, as at 20, from said portion 19, so as to constitute the bottom of the pouch, and is thence preferably curved, as at 21, and carried upwardly as at 22 whereby to provide the opposite end wall of the pouch. Preferably, the two side sheets 16 of the lining material are stitched together for a short distance along their lower marginal portions, as at 23, in the region of the open end portion of the device where the pipe receptacle is provided. This lining is loose throughout from the outer casing 10, except at its marginal portion, where it is attached with the interposed tapes 15, which carry the closure members 14. In the manufacture it is preferable to first cement the tapes 15 to the marginal portions of the lining sheets 16 and then stitch the parts together along the line 24. The lining as thus produced constitutes a unitary structure which is readily inserted for final assembly within the outer casing 10, said casing being obviously formed as a separate unitary structure by merely stitching two counterpart sheets together inside out, as at 25, along one side and one end, and then turning the casing to bring the overlapped marginally seamed portions on the inside, as shown more clearly in Figs. 4 and 5 of the drawings.

In applying the lining structure to the cas-

ing 10 the adjacent marginal portions of the casing are preferably cemented to the tapes 15, after which the parts are further secured by stitching along the line 26 near the extreme marginal portion of the casing.

5 By attaching the lining sheets 16 and side walls of the outer casing 10 only along the adjacent marginal portions at the open side and end of the device, and providing the gus-
10 set member 18 between the walls of the lining to constitute the pouch or receptacle for the tobacco, ample provision is thereby made for the desirable flexibility and expansibility in a device of this character, which is an ad-
15 vantage in utility, in addition to facilitating assembly and effecting economy in manufac-
ture.

Preferably, the pouch portion proper, or tobacco receptacle of the device, is provided
20 with a flap 27 at one side, which may be folded over the upper portion of the pocket for the purpose of retarding evaporation of the moisture in the tobacco and thereby keeping it in its proper condition for smoking. The lower
25 portions of the side sheets 16 of the lining, below the pouch portion 11, while being detached throughout from the outer casing 10, afford a flexible and compensating lining which keeps the stem of the pipe from com-
30 ing in direct contact with the outer casing, and the short line of stitching 23 which lies within the receiving portion of the device for the bowl of the pipe, affords a neat finish for the outer portion of the lining
35 which is exposed when the casing is opened for the insertion or removal of the pipe.

Obviously, the structure may be modified in many respects without in the least departing from the spirit and scope of the invention as defined by the appended claims. The invention, therefore, is not limited to the specific construction and arrangement shown in the accompanying drawings.

Having thus described my invention, what
45 I claim as new and desire to secure by Letters Patent is:

1. In a device of the character described, an outer casing constructed of flexible sheet material, and a lining secured marginally to
50 the adjacent opening marginal portion of the casing but being otherwise detached from said casing, a portion of said lining being fabricated into a pocket opening coincidentally with the opening marginal portion of the cas-
55 ing and constituting a pouch for containing tobacco, the remainder of said lining material affording a lining for a pipe receptacle comprising the portion of the casing not oc-
cupied by said pouch, the opening marginal
60 portions of both the tobacco pouch and pipe receptacle being controlled by a common closure element.

2. In a device of the character described, an outer casing constructed of flexible sheet
65 material, closed at one side and one end and

opening at the opposite side and end, a com-
mon closure for the opening side and end of
70 said casing, and a lining secured marginally to the adjacent marginal portion of said cas-
ing in the region of the opening side and end
thereof, said lining being otherwise detached
from the casing, a gusset secured at its longi-
75 tudinal margins to said lining, constituting
end and bottom walls of a tobacco pouch and
the portion of said lining not included with-
in the pouch affording a lining for a pipe re-
ceptacle comprising the portion of the outer
80 casing not occupied by said pouch.

3. In a device of the character described,
an outer casing comprising opposite wall
85 sheets secured marginally at one side and
one end and being detached at the opposite
side and end, a common closure of the slide
control type for the opening side and end
of said casing, a lining within said casing
90 and covering the entire interior thereof, said
lining being secured marginally to said outer
casing along the marginal portions of its
opening side and end, but being otherwise
detached from said casing, a gusset secured
95 at its longitudinal margins to said lining,
constituting end and bottom walls of a pouch
of which said lining constitutes the side walls,
and the portion of the structure not occupied
by said pouch constituting an L-shaped pipe
100 receptacle, the portion of said lining not in-
cluded within the pouch affording a lining
for said pipe receptacle.

4. As an article of manufacture, a com-
bined tobacco pouch and pipe holder, com-
prising an outer casing produced by securing
105 together marginally at one side and one end
two rectangular sheets of flexible material as
a unitary part, said casing sheets being other-
wise detached, and a unitary lining of air-
tight and moisture-proof material comprising
110 sheets of approximately the same size
and of the same general marginal contour as
said casing sheets, an interposed gusset strip
secured at its longitudinal margins to said
lining sheets, constituting end and bottom
115 walls of a pouch, and a closure for the device
of the continuous releasable interlocking type
and comprising tapes on which the inter-
engageable elements of said closure are mount-
ed, said tapes being secured marginally to the
adjacent marginal portions of said outer cas-
ing and lining at the opening side and end
120 of the device, and a sliding controlling ele-
ment common to all of said interengageable
closure elements, the portion of the struc-
ture not occupied by said pouch constituting
a pipe holder.

5. As an article of manufacture, a com-
bined tobacco pouch and pipe holder con-
structed of flexible sheet material, perma-
nently closed at one end and one side but
opening throughout the extent of the oppo-
site side and end, the pouch portion compris-
125 ing a pocket extending from the closure end
130

and terminating short of the opening end and closed side of the structure, said pocket opening coincidentally with the opening side of the structure, the structure including a
5 unitary outer casing comprising two side wall sheets secured together marginally at the closed side and end of the article, and a moisture-proof lining comprising two side wall sheets of approximately the same size
10 and general marginal contour as said outer casing wall sheets, said lining sheets being respectively attached to the longitudinal margins of a gusset strip constituting the bottom and end walls of the pouch portion
15 of the article, said lining wall sheets being marginally secured to the adjacent marginal portions of the outer casing wall sheets throughout the extent of the opening side and end of the structure, the portion of the structure not occupied by said pouch constituting
20 a lined substantially L-shaped pipe holder, and a common sliding closure for the opening side and end of the article.

6. A combined tobacco pouch and pipe holder as set forth in claim 5, one of said lining sheets having a flap extension affording an internal closure for the opening side of the pouch portion of the article.

In testimony whereof I have signed my
25 name to this specification.

MICHAEL J. McGUIRE.
